UNITED STATES PATENT OFFICE.

ARVIN R. PAULL, OF MONTREAL, QUEBEC, CANADA.

PAPER-STOCK-SCREENING MACHINE.

1,149,534.

Specification of Letters Patent. Patented Aug. 10, 1915.

Application filed April 17, 1914. Serial No. 832,599.

To all whom it may concern:

Be it known that I, ARVIN R. PAULL, a citizen of the United States, residing at the city of Montreal, in the Province of Quebec and Dominion of Canada, have invented certain new and useful Improvements in Paper-Stock-Screening Machines, of which the following is a full, clear, and exact description.

This invention relates to improvements in screens for paper stock and like material, and the object is to provide a simple, durable and compact machine for removing splinters, sand, and foreign material from paper pulp before it is passed into the paper making machine.

15 A further object is to provide a lighter and more compact machine having larger screening capacity and higher screening efficiency than machines at present in general use.

20 A still further object is to provide a screening device in which the vibration and consequent noise are retained as much as possible in the machine itself.

25 The diaphragm screens at present in general use consist of a series of horizontal screens which are vibrated by means of a cam shaft located beneath. The vibration of the diaphragm operates to draw the material through the perforations or slots thereof, the foreign matter being held back. These screens are set out in a row and the flow of material passes thereover, a portion being drawn through each screen. These machines 30 are extremely heavy and cumbersome.

35 In the present invention, a polygonal cage is formed between the bars of which the screen plates are mounted. This screen cage is revolvably mounted upon a slowly revolving shaft, provided with a cam which engages shoes coöperating with the spindles of a series of plunger plates or pistons. The action of the cam imparts a vibrating or reciprocating motion to the plunger plates, 40 and the paper stock is forced or sucked through the superposed and relatively stationary screen plates. Means are provided for conveying the splinters, sand, etc., to a discharging point where they are flushed off 45 the screens.

50 In the drawings which illustrate the invention:—Figure 1 is an end elevation of the device with a portion of the casing broken away. Fig. 2 is a sectional view on the line 2—2, Fig. 1. Fig. 3 is a cross sectional view on the line 3—3, Fig. 2. Fig. 4

is an enlargement of the central portion of Fig. 3 showing the throw of the cam exaggerated. Fig. 5 is a half plan view of one of the screening plates.

60 Referring more particularly to the drawings, 11 designates a cylindrical casing, mounted on legs 12 and provided at the top with a suitable opening 13 parallel with the axis. One end 14 of the casing is preferably 65 solid, while the other end 15 is provided with a large inspection opening 16 in the upper part thereof, and with a small discharge opening 17 in the lower part. At each end of the casing, bearings 18 are provided.

70 Within the casing, a cage is located consisting of polygonal spoked end members 19 connected by radially disposed separating blades 20, arranged longitudinally parallel with the axis of the cage. These blades 75 20 are secured to the end members 19 at the junctions of the faces thereof, as will be clearly seen from the drawings. Each of the end members 19 is provided with a circular flange 21 near the periphery thereof, which 80 abuts similar flanges 22 formed on the inner sides of the casing ends. A circular packing ring 23 is provided surrounding the flanges 21 and 22, and forming therewith a sufficiently tight joint to prevent the passage of 85 the paper stock between the casing and cage ends. The cage is rigidly mounted on a hollow shaft 24 which revolves in the bearings 18 and 19 and is driven at suitable speed by means of a pulley 25 or any suitable gearing. The shaft 24 is enlarged midway 90 between the ends of the cage to form a cylindrical cam box 26. A solid shaft 27 driven at comparatively high speed by means of a pulley 28 or other suitable arrangement passes through the hollow shaft 95 24 from end to end. Mounted on the shaft 27 within the cam box 26 is a small cam 29 having a plurality of very slight throws. This cam is shown much exaggerated in Fig. 100 4 as having three throws or projecting portions, but this number may be varied as desired. The throw of this cam is very small, being in reality only about three-sixteenths of an inch for a cage of six feet or more 105 diameter.

110 Between the partition blades 20 of the cage, rectangular plungers or pistons 30 are provided, each plunger plate occupying the space from one blade to the next, and preferably from end plate to end plate of the cage. The plunger plates 30 are each

- mounted on a radial spindle 31 which passes into the cam box 26 through stuffing boxes 33. Each spindle is provided with a head 34 having a removable shoe 35 pressing 5 against the cam 29. Springs 36 are provided to hold the shoes always against the cam, so that reciprocating motion will be imparted to the spindles 31. The load of these springs is suitably adjusted by means of set screws 10 37. Mounted above the plungers 30 are screening plates 30^a, which plates are rectangular in shape and set between the separating blades 20. These screening plates are provided with perforations or slots 32 of 15 suitable size and shape. In some instances, elongated slots such as shown in Fig. 5 will be preferred, while in other instances much shorter perforations which may be circular are preferred.
- 20 It will be noted in Figs. 1 and 3 of the drawings that the screen cage is mounted eccentrically within the casing 11, the eccentricity being in a horizontal direction. Each 25 of the separating blades 20 is provided with a scraper 38 projecting beyond the cage. As the screen cage revolves, the scrapers gradually approach the casing until they come into contact therewith, as clearly shown in Fig. 3. The splinters and other foreign 30 matter which have been separated from the pulp are thus carried upwardly against one side of the casing to a suitable point where a flush pipe 39 is provided in one end of the casing and a drain pipe 40 in the other end.
- 35 A rush of water is thus maintained over the surface of each plate, as it passes this point so that all foreign matter is carried away by the water. To insure absolute cleaning of the screening plates, a spray pipe 41 is located 40 above the opening 13 and water is sprayed over the entire surface of the plate, which is thus washed clean and cleared of any particles of stock remaining in the perforations thereof.
- 45 Paper stock to be screened is delivered into the casing, for instance, through the aperture 13, and approximately fills the space between the casing and the screen plates. As the screening cage revolves, this 50 paper stock is carried around by the scrapers 38 into the constantly narrowing space caused by the eccentricity of the cage and casing. During this movement, which results in a very slight compression of the stock, the rapidly revolving cam successively 55 engaging the shoes of the several spindles 31 causes the plungers to have a vibrating or reciprocating movement toward and away from the axis of the cage. During the outward movement of each plunger, a small amount of stock may be forced through the 60 perforations of the screen plates so that such perforations are prevented from clogging.
- 65 During the return movement of the plungers, the pulp stock is sucked through the

screen plates into the space between said plates and the plungers. In this way, each successive vibration of the plungers forces or sucks a little more pulp through, so that the interior of the cage becomes partially 70 filled with the screened stock, which is discharged through the aperture 17. The paper stock fills whatever space there is between the edges of the plunger plates and the blades and cage ends, and acts as a seal 75 so that the sucking or forcing action of the plungers is not hampered by leakage around the edges. The splinters, sand and other foreign matter which cannot pass through the perforations of the screen plates remain 80 outside, and are carried by the scrapers 38 to the flushing point, as previously described.

In practice, the cage is preferably operated at about one revolution per minute or a trifle faster, while the cam shaft turns approximately two hundred revolutions a minute. These speeds may, however, be varied according to the quality of stuff treated and the completeness of the screening required. 90 The shape of the cam in a large measure opposes the vibrations to one another, and the nature of the machine centers all these vibrations at the axis of the rotor, so that only a minimum of vibration is transmitted to the building in which the machine is installed. The rotating cage carries the stuff around with it, so that screening is accomplished much more rapidly than when the stuff merely runs over the screens. Furthermore, the vibrating action of the plungers tending to draw or force material through the perforated screens adds greatly to the rapidity and effectiveness of the machine. 95 To insure smooth running, and minimize the noise and the vibration, the cam box 26 may be filled with heavy oil or grease, which is prevented from leaking out and mingling with the stock by the stuffing boxes 33. This oil may also be led through grooves of well 100 known design in the hollow shaft 24 so as to lubricate the cam shaft 27.

While the device has been shown with screen plates extending from end to end of the cage, it is obvious that as many plates may be used in this length as desired, and each series of plates thus formed operated by its own cam. In the same way, long blades may be operated at each end by means of two cams. Various other mechanical changes may be made without departing from the spirit of the invention, which is not limited to the particular form shown.

Having thus described my invention, what I claim is:

1. A device of the character described, comprising a casing, an eccentrically mounted cage within the casing, a series of substantially flat screens mounted on the circumference of said cage, and a series of in.

10 intermittently operating plungers mounted within and adjacent to said screens.

15 2. A device of the character described, comprising a casing, an eccentrically mounted rotating screen cage therein, a series of flat screening plates mounted on the circumference of said cage, a series of intermittently operating plungers mounted within said cage adjacent the screening plates, and means for imparting a successive, intermittent motion to said plungers.

20 3. A device of the character described, comprising a casing, a rotating cage therein, a series of separating bars mounted in said cage, a series of flat screen plates fixed between said separating bars, and a series of plungers mounted within and adjacent the screening plates.

25 4. A device of the character described, comprising a casing, a rotating cage therein, a series of separating bars mounted in said cage, a series of flat screen plates fixed between said separating bars, a series of vibrating plungers mounted within and adjacent the screen plates, and means for imparting successive, intermittent motion to said plungers.

30 5. A device of the character described, comprising a casing, a rotating screen cage therein, vibrating plungers mounted in said screen cage, and scrapers carried by the screen cage arranged to circulate material to be screened within the casing.

35 6. A device of the character described, comprising a casing, an eccentrically mounted cage within the casing, a series of screens mounted in said cage, a series of radially disposed rigid stemmed plungers mounted adjacent said screens and radially movable.

40 7. A device of the character described, comprising a casing, an eccentrically disposed screening mechanism revoluble therein, intermittently vibrating plungers in said screening mechanism, scrapers carried by said screening mechanism adapted to circulate the material to be screened, and means for maintaining a flow of water across the screen plates.

45 8. A device of the character described, comprising a casing, a screen cage revolubly mounted therein, a plurality of perforated screen plates secured to said screen cage, independently movable plungers mounted below said plates, and a cam adapted to intermittently reciprocate said plungers with respect to the perforated plates.

50 9. A device of the character described, comprising a casing, an eccentrically mounted cage within the casing, a series of screens

55 mounted in said cage, a series of radially disposed rigid plunger units mounted adjacent said screens and radially movable, and means for limiting the inward movement of said plunger units.

60 10. In a device of the character described, the combination with a casing, of a cage revoluble therein, screening plates mounted in said cage, a plurality of independently movable plungers mounted below said screening plates, a hollow shaft supporting 70 the cage, a second shaft mounted within the hollow shaft, a cam mounted on said inner shaft, and spindles supporting said plungers and engaging said cam.

75 11. In a device of the character described, the combination with a casing, of a cage revolvably mounted therein, a plurality of plungers and superposed perforated plates mounted on said cage and forming together a polygonal screen, means for vibrating 80 said plungers independently, and means for cleaning the foreign matter from the surface of said plates.

85 12. A device of the character described, comprising a casing, a cage therein, a plurality of independently movable plungers and stationary screen plates mounted on said cage and forming a substantially cylindrical screen, scrapers carried by the cage intermediate said plates arranged to transport material to be screened, a hollow shaft revolvably supporting said cage, a solid cam shaft within said hollow shaft, spindles carried by said plungers engaging said cam shaft, means for holding said spindles in engagement with the cam shaft whereby vibratory motion will be imparted to said plungers, means for supplying material to be screened into the annular space between the screen and casing, means for removing 95 material passed through the screen from the interior of the cage, means for washing away material not passed through the screen, and means for washing obstructions out of the screen.

100 13. A device of the character described comprising a casing, an eccentrically mounted cage within the casing, a series of radially disposed radially movable rigid plunger units mounted adjacent said screens and 110 guiding means for said plunger units.

In witness whereof I have hereunto set my hand in the presence of two witnesses.
